UNITED STATES PATENT OFFICE.

JOHN KARITZKY, OF GARWOOD, NEW JERSEY, ASSIGNOR TO HENRY B. NEWHALL, JR.,
OF PLAINFIELD, NEW JERSEY, EXECUTOR OF HENRY B. NEWHALL, DECEASED.

SPRING-TOGGLE.

1,374,926.

Specification of Letters Patent. Patented Apr. 19, 1921.

Application filed December 23, 1919. Serial No. 347,033.

To all whom it may concern:

Be it known that I, JOHN KARITZKY, a citizen of the United States, residing at Garwood, in the county of Union and State of New Jersey, have invented certain new and useful Improvements in Spring-Toggles, of which the following is a specification, taken in connection with the accompanying drawings.

10 My invention relates to toggles. More particularly it relates to means which will insure that the toggle head will rock or swing at an angle to the arm or bolt, after it has been inserted into the wall or other support.

My invention further relates to a toggle having a head provided with pivoting means midway its length, so that one end does not overbalance the other, and means 20 to insure the rocking of the toggle head when it has been inserted in the wall.

My invention further relates to a rigid toggle head which is swung upon the pivoting nut by spring means; it further relates 25 to a rigid toggle head having bearings for a pivoting nut, and to a spring coöoperating with the nut to hold the nut within the bearings.

My invention further relates to a rigid 30 toggle head having a pivoted nut, and a spring carried by the toggle head having an arm coöoperating with the nut to rock the toggle head in relation to the nut. My invention further relates to such a device in 35 which the arm of the spring may be extended and bent at an angle so that the arm co-operates not only with the nut but also with the bolt.

My invention further relates to certain 40 combinations and details of construction which will be more fully hereinafter described in the specification and pointed out in the claims.

In the accompanying drawings the same 45 reference numerals refer to similar parts in the different figures.

Figure 1 is a perspective view of my 50 spring toggle bolt, one of the flanges being omitted from the toggle head for purposes of clearer illustration;

Fig. 2 is a vertical section through a wall, or other support, and the work to be supported showing the manner of positioning the spring toggle which is shown in side elevation;

Fig. 3 is a vertical section through a wall or other support, and the work supported, the same as in Fig. 2, but showing the toggle head rocked at right angles to the bolt by means of the spring;

Fig. 4 is a perspective view of the preferred form of spring used in my invention;

Fig. 5 is a perspective view of the toggle head; and

Fig. 6 is a perspective view of my toggle 65 head, the same as Fig. 1, but omitting the bent extension of the spring arm.

In the toggle bolts now on the market it is customary to pivot the arm or bolt to the head so that one end of the head is heavier 70 than the other. That is, the pivot is not located substantially midway between the ends of the head. By having one end longer, that end will be heavier than the other end, and consequently will have a 75 tendency to overbalance it and cause the toggle head, as soon as it is pushed home, to assume an angle to the arm or bolt to which it is pivoted. A very slight obstruction inside the wall or support however will 80 prevent gravity turning the head at right angles to the hole, so that the work can be secured to the wall. Such toggle heads also have been found objectionable in practice in that a comparatively long head has to be 85 used to obtain the overbalancing feature.

By my invention I positively insure that the toggle head will assume a position at an angle to the hole, through which it has been inserted, even though it should scrape upon 90 some slight obstruction which would be sufficient to prevent the ordinary form of gravity toggle from operating. Further I can make my toggle head of minimum length which will not only save metal, and 95 therefore cost of manufacture, but it will permit my toggle to be used in thin partitions, or similar walls or structures, where the free space in which the toggle has to turn or swing is too limited for the ordinary 100

gravity toggle which has to be of unnecessary length to obtain the overbalancing feature.

In my invention the toggle head is rigid 5 and preferably formed of one piece of sheet metal, which gives the maximum strength in spanning the opening in the wall.

In the illustrative embodiment of my invention shown in the drawing the toggle 10 head 1, Fig. 5 is provided with two flanges, 2 and 3 at preferably right angles to the base 4. In the flange 3 a hole 5 is struck out and in the flange 2 a slot 6 having a curved portion 7 at its lower end is struck 15 out or otherwise formed. The pivoting nut 8 is readily located in the toggle head 1 by inserting one of its trunnions 9 in the hole 5 and permitting the other trunnion 9 to drop into the slot 6. While this is an easy 20 way of locating the nut in the toggle head, this connection would not be stable or permanent for the slightest jarring would cause the trunnion in the slot 6 to fall out, which would then permit the other trunnion 9 to 25 become disengaged from the hole 5. To insure the nut 8 being securely held within the toggle head 1, I close the slot 6 by some suitable means. This closing means has also an additional function, that of assisting in 30 rocking the toggle head 1 with relation to the bolt 10.

I preferably employ a spring closing means and preferably a coil spring 11, having an arm 12 and an arm 13. The coil 35 spring 11 is secured to the toggle head 1 in any suitable manner such as by bending down fingers 14, 14 from the base 4 of the toggle head. The arm 12 is secured to the toggle head in any suitable manner, such as 40 striking up a finger 15 from the flange 3. The other arm 13 of the spring 11 extends substantially parallel with the base 4 and over one of the flat trunnions 9, or similar surface, of the nut 8, closing the slot 6.

45 It will be clear from Fig. 6 if the end 16 of the toggle head 1 is bent down by the thumb, so that it is brought in contact with the stove bolt 10, that the arm 13 of the spring 11 will be put under tension. As 50 soon as the pressure of holding the end 16 in contact with the stove bolt 10 is released, the resiliency of the spring 11 will cause the toggle head 1 to assume the position shown in Fig. 6.

55 Preferably, though not necessarily, I extend the arm 13 to form an extension 17, Figs. 1, 2, 3, and 4. In this preferred construction the stove bolt 10 is passed through the work 18, to be supported on the face 19 60 of the wall or other suitable support 20, and is then threaded into the nut 8. By then bringing the end 16 into alignment with the stove bolt 10 the toggle bolt 1 is forced into the hole 21 of the wall or support 20 which will cause the extension 17

of the arm 13 to engage with the stove bolt 10 and put the spring 11 under greater tension than if the arm 13 simply bore upon one of the trunnions. As soon as the end 16 escapes the rear face 22 of the wall or 70 support 20 the spring 11 will immediately cause the head to fly with a quick sharp snap into the position shown in Figs. 3 and 1, the latter figure showing my spring toggle holding the work 18 firmly against the 75 face 19 of the wall or other suitable support 20.

My toggle bolt will work satisfactorily without the bent extension 17 on the arm 13, this latter construction being shown in 80 Fig. 6, previously described. But with the extension 17 engaging with the stove bolt 10 greater tension is exerted upon the spring 11 which insures a quicker and snappier action as soon as the toggle head 85 reaches the inner surface of the wall or other suitable support 20.

Having thus described this invention in connection with an illustrative embodiment thereof, to the details of which I do not 90 desire to be limited, what is claimed as new and what is desired to secure by Letters Patent is set forth in the appended claims.

What I claim is:—

1. A new article of manufacture comprising a toggle head having side flanges, one of the flanges being provided with a hole to coöperate with a trunnion of a nut, the other flange being also provided with a similar hole and with a slot extending 100 transversely to the longitudinal axis of the toggle head to permit the other trunnion of the nut to drop into the second hole.

2. The combination of a toggle head having a bearing to receive one trunnion of a 105 nut, and a slot at right angles to the longitudinal axis of the toggle head to receive the other trunnion of a nut, a nut provided with trunnions to coöperate with the bearing and the transverse slot, and a bolt to 110 coöperate with the nut.

3. The combination in a toggle head provided with bearings for a nut, a nut, and a spring to hold the nut in the bearings.

4. The combination in a one piece toggle 115 head provided with bearing for a nut, a nut, a spring adapted to bear upon the nut, and means for securing the spring to the toggle head.

5. The combination in a toggle head provided with bearings for a nut, a nut pivoted in said bearings, a spring provided with two arms, means to secure the spring and one arm to the toggle head, the other end of the spring adapted to bear upon the 125 nut.

6. The combination in a toggle head provided with bearings for a nut, a nut pivoted in said bearings, a coil spring provided with two arms, means to secure the 130

coil spring and one arm to the toggle head, the other end of the coil spring adapted to bear upon the nut.

7. The combination in a toggle head provided with bearings for a nut, a nut pivoted in said bearings, a bolt coöperating with the nut, a spring provided with two arms, means to secure the spring and one arm to

the toggle head, the other end of the spring coöperating with both the nut and bolt to 10 rock the toggle head at an angle to the bolt.

JOHN KARITZKY.
